Henry G. Fiske

UNITED STATES PATENT OFFICE.

HENRY G. FISKE, OF SPRINGFIELD, MASSACHUSETTS.

RATCHET AND CLUTCH DEVICE.

SPECIFICATION forming part of Letters Patent No. 243,366, dated June 28, 1881.

Application filed March 12, 1881. (No model.)

To all whom it may concern:

Be it known that I, HENRY G. FISKE, of Springfield, in the county of Hampden and State of Massachusetts, have invented a new 5 and useful Improved Ratchet or Clutch Device, of which the following is a full, clear, and exact specification and description, reference being had to the accompanying drawings, making a part of this specification, and to the letters and figures of reference marked thereon.

The object of my invention is to provide a cheap and effective ratchet device for driving a shaft or train of wheels only in one direction from another shaft or wheel adapted to revolve 15 in both directions; and I accomplish this by the mechanism substantially hereinafter described, and illustrated in the accompanying drawings, in which—

Figure I is a side view of a driving-wheel 20 with the ratchet-wheel connected therewith. Fig. II is a transverse section of the same at line A. Fig. III is a side view of the driving-wheel, with one of the pawls in position and the other removed, and showing the socket in 25 which it operates. Fig. IV is an inside view of the ratchet-wheel, showing the ratchet-teeth cast thereon. Fig. V is a transverse section of the driving-wheel at line B. Fig. VI is a plan view of the pawl. Fig. VII is an edge view of 30 the same, and Fig. VIII is a reverse edge view of the same.

In the drawings, 1 denotes a driving-wheel adapted to be either fixed upon a shaft or to rotate thereon, upon one side of which is cast 35 an annular flange, 4, projecting to the desired distance, and inside of which are cast any desired number of sets of bosses, as 6, two in each set, as shown clearly in Figs. III and V, to form a socket to receive the trunnion on the 40 pawl. In the accompanying illustration I have shown two sets of bosses, one set opposite the other.

The pawl 5 is made preferably curved on the outer edge, to conform approximately to the inner surface of the flange 4, and is provided on one side with a trunnion-shaped protuberance, 45 e, which I denominate a "trunnion."

Although this ratchet device may be used either side uppermost in a horizontal position 50 or in a vertical position, I prefer, for the purposes of this description, to designate the side

of the pawl opposite the trunnion as its "upper" side. This pawl terminates at one end somewhat sharply, as at a, the face of which end is preferably radial to its outer curved edge, 55 and whose extreme end projects a little above the upper side of the pawl, as shown in Figs. VII and VIII, and the upper side of the pawl is also provided with a protuberance, e, near its opposite end, projecting also a little above 60 the upper side of the pawl, as shown also in Figs. VII and VIII.

The trunnion e fits loosely its socket between 65 each set of bosses, so that the pawl will tilt easily on its trunnion.

The wheel 2 is adapted to be either fixed on a shaft, or to rotate thereon, and, if it is intended to communicate motion to a train of wheels, is provided with teeth on its periphery or on its side, and on one side are cast ratchet-teeth 70 3, arranged in circular order, as shown clearly in Figs. II and IV, and the outer edge of the circle of teeth 3 just passes inside the annular flange 4 when the wheel 2 is placed against the flange, so that the wheels will turn 75 easily in that position.

Any number of the pawls 5, with a set of bosses, 6, for each, may be used; but two pawls will be quite sufficient for most purposes, and one pawl will be quite operative, the advantages of two being hereinafter explained. 80

This ratchet device may be used either to drive a shaft, or to drive a wheel or a train of wheels, and the wheel 1 may be secured to a fixed shaft so as to revolve freely thereon; or 85 it may be securely keyed or fixed to a revolving shaft, in either case so that the wheel 1 may be revolved in either direction.

The wheel 2 may be keyed or secured permanently to a revolving shaft, in which case it 90 will give motion to said shaft in one direction; or it may be secured to a fixed shaft so as to revolve freely thereon independently of the shaft, in which case spur-teeth may be made on the periphery of the wheel, or on its side, to gear 95 into another wheel or set of wheels, which will then be driven in only one direction by the wheel 2.

The operation of the device is such that when the wheel 2 is placed against the flange 4 of the 100 wheel 1, and with the pawls 5 in place, as shown clearly in Fig. II, as the driving-wheel

1 is revolved the pawls 5 move around against the outer ends of the ratchet-teeth 3, the protuberance *c* being depressed between two teeth by the projecting end *a* of the pawl riding 5 against another tooth, and the extreme end *a* of the pawl being depressed between two teeth into position to engage against one of them by the protuberance *c* riding against a tooth, so that the engaging end *a* of the pawl is always 10 forced into position to engage against a tooth by the contact of the other end of the pawl with the outer surface of another tooth.

It is preferable to arrange the teeth and pawls so that only one pawl will engage with 15 a tooth at one and the same time, so that the engagement will occur as quickly as possible, and with the minimum amount of lost motion of the driving-wheel. If an odd number of ratchet-teeth 3 be used, and two pawls be used of the 20 same size and placed opposite each other, only one of the pawls will engage at a time against a tooth, and the lost motion before engagement will be only half as much as when a single pawl is used.

25 It is evident that this ratchet device is adapted to be used in connection with many different machines, and is equally operative in one position as another, whether placed horizontally, either side uppermost, or vertically. 30 It has the advantage also of being cheap, as every part may be cast and be put together just as it comes from the foundry and without any finish whatever, and in its operation it is positive, as the pawl is forced into position to 35 engage with every tooth by the contact of each

tooth, as they revolve, with the protuberance on the pawl at *c*, instead of the uncertainty incidental to the use of springs.

I denominate the space between each two bosses 6 the "trunnion-socket," as each set of 40 bosses forms a socket to receive the trunnion of the pawl, in which the latter may vibrate or tilt.

The annular flange 4 may be made with numerous perforations of various and ornamental 45 forms; or it may extend only partially around, and only at that portion where the pawls are located, to keep them in place; but I prefer in practice to make it, as shown in the drawings, extending around the entire circle and 50 solid, to hold the pawls in place and exclude dirt and other matter therefrom.

Having thus described my invention, what I claim as new is—

The combination, with a driving-wheel, of a 55 ratchet-wheel having a series of ratchet-teeth on its side arranged in a general circular form, a pawl adapted at one end to engage with said ratchet-teeth, and having a trunnion on one side and a protuberance on the opposite side, 60 near its end, against which said ratchet-teeth impinge when moving past said teeth, and a socket on the side of said driving-wheel to receive the trunnion of said pawl, and in which the latter may tilt, substantially as described.

HENRY G. FISKE.
